UNITED STATES PATENT OFFICE.

ARTHUR DOUGLAS NASH, OF NEW YORK, N. Y.

LIGHT UNIT.

1,151,377.

Specification of Letters Patent. Patented Aug. 24, 1915.

Application filed March 24, 1915. Serial No. 16,778.

To all whom it may concern:

Be it known that I, ARTHUR DOUGLAS NASH, a citizen of the United States, and a resident of the city of New York, Flushing, 5 borough of Queens, in the county of Queens and State of New York, have invented a new and Improved Light Unit, of which the following is a full, clear, and exact description.

The invention relates to electric lighting 10 and its object is to provide a light unit which includes an electric lamp and a decorative covering such as a globe containing the bulb of the electric light and having its neck detachably connected with an extension 15 of the base of the lamp adjacent the bulb to leave the usual screw-threaded shank of the base wholly unobstructed for attachment to a socket.

In order to accomplish the desired result, 20 use is made of an electric lamp having a bulb and a base, the base having an outer portion adapted to be fastened in a socket and having an extension adjacent the bulb, and a decorative covering having a neck for the 25 passage of the bulb interiorly of the decorative casing, the neck of the latter fitting on and being secured to the said base extension of the electric lamp.

A practical embodiment of the invention 30 is represented in the accompanying drawings forming a part of this specification, in which similar characters of reference indicate corresponding parts in all the views.

Figure 1 is a side elevation of the electric 35 lamp; Fig. 2 is a side elevation of the light unit as applied and with the decorative covering shown in section, a portion of the attaching socket being also shown in section; Fig. 3 is a side elevation of a modified form 40 of the electric lamp; Fig. 4 is a side elevation partly in section of a modified form of the light unit; and Fig. 5 is a reduced side elevation of a plurality of light units in position on a chandelier.

The light unit in its general construction 45 consists of an electric lamp A and a decorative covering B, preferably in the form of a globe of decorative glass or other diaphanous material. The electric lamp A consists 50 of a cylindrical bulb C, a base D and a suitable filament E, the base D being of metal and having a threaded portion D' adapted to screw into a suitable electric lamp socket F. The base D is further provided with an enlarged extension D² adjacent the bulb C and this enlarged portion D² is adapted to be en-

gaged by a collar G held on the neck B' of the covering B. As shown in Figs. 1 and 2, the enlarged portion D² is exteriorly screw-threaded and the collar G is provided with an interior screw thread G' screwing on the threaded portion D² so as to securely fasten the decorative covering B to the electric lamp A to form a part thereof. It will be noticed that the opening in the collar G is sufficiently large for the passage of the bulb C into the decorative covering B for the latter to inclose the said bulb C, as plainly shown in Figs. 2 and 4.

In order to limit the relative screwing 70 movement of the collar G on the threaded portion D², use is made of a limiting flange D⁷ fixed on the base D adjacent the upper end of the threaded portion D² so that when the collar G is screwed up on the threaded 75 portion D² the collar G finally abuts against the flange D⁷. It will be noticed that by this arrangement the covering B is held against being screwed up too far and the bottom of the bulb C is prevented from contact with 80 the bottom of the covering B.

Instead of fastening the decorative covering B to the lamp A as described and shown in Figs. 1 and 2, use may be made of the construction illustrated in Figs. 3 and 4. In 85 this case the base D³ of the electric lamp A is provided with the threaded portion D⁴ adapted to screw into the socket F, and the base is further provided with an enlarged extension D⁵ provided at diametrically opposite sides with bayonet slots D⁶ adapted to be engaged by lugs G² struck up on the inner side of the collar G³ held on the neck B' of the decorative covering B. By the arrangement described the decorative covering 90 B can be readily placed in position over the bulb C and fastened in position on the extension D⁵ by engaging the lugs G² with the bayonet slots D⁶ in the usual way. I do not limit myself to the construction shown and 95 described for fastening the decorative covering B to the electric lamp C, as the same may be varied without deviating from my invention.

It will be noticed that by the arrangement 105 described, the decorative covering B and the electric lamp A form a light unit which can be readily screwed in any socket F, for instance, as shown in Fig. 5, a number of light units are screwed into sockets F held on a chandelier ring H. It will also be noticed that in a case of this kind a decorative cov-

ering could not well be attached to the chandelier, but with my improved construction it is only necessary to screw the light unit in position in the socket F of the chandelier.

5 If desired, the decorative covering B may be of colored glass with suitable designs, or the covering B may be of plain glass in the upper portion and colored glass in the lower portion, as shown in Fig. 5, to insure a bright illumination in a room without the observer looking directly onto the incandescent filament E, which latter is shaded by the lower portion of the decorative covering.

10 It is understood that by the arrangement described, no separate fixtures are required for holding the globe in place, and the electric lamp and the globe form a unitary structure which can be readily placed in position in a lighting fixture by merely screwing the threaded base portion D' (or D⁸) in the socket of the lighting fixture.

15 Having thus described my invention, I claim as new and desire to secure by Letters

20 Patent:

25 1. A light unit, comprising an electric lamp having a bulb and a base, the base having an integral outer portion adapted to be fastened in a socket and having an extension 30 adjacent the bulb, and a decorative covering adapted to inclose the said lamp bulb and having a neck provided with a metallic collar fitting exteriorly on and being secured to the said base extension of the electric 35 lamp.

40 2. A light unit, comprising an electric lamp having a bulb and a base, the base having an integral outer threaded portion adapted to screw into a lamp socket and having an enlarged exteriorly threaded integral extension adjacent the bulb, and a globe having a neck for the passage of the said lamp bulb into the globe, the neck having a threaded collar screwing exteriorly onto 45 the said threaded extension to unite the globe and the lamp.

45 3. A light unit, comprising an electric

lamp having a bulb and a base, the base having an outer threaded portion adapted to screw into a lamp socket and having an 50 enlarged exteriorly threaded extension adjacent the bulb and a globe of diaphanous decorative material and having a neck for the passage of the said lamp bulb into the globe for the latter to inclose the bulb, the 55 said neck having fastened thereto a metallic collar provided with an interior screw thread screwing on the said lamp base extension.

60 4. A light unit, comprising an electric lamp having a bulb and a base, the base having an outer integral portion adapted to be fastened in a socket and having an integral extension adjacent the bulb, a decorative covering adapted to inclose the said lamp 65 bulb and having a neck provided with a metallic collar fitting exteriorly on and being secured to the said base extension of the electric lamp, and means for limiting the movement of the extension relative to the 70 said collar of the covering neck.

75 5. A light unit, comprising an electric lamp having a bulb and a base, the base having an outer threaded portion adapted to screw into a lamp socket and having an enlarged exteriorly threaded extension adjacent the bulb, a globe of a diaphanous decorative material and having a neck for the passage of the said lamp bulb into the globe for the latter to inclose the bulb, the said 80 neck having fastened thereto a metallic collar provided with an interior screw thread screwing on the said lamp base extension, and a limiting flange integral on the base adjacent the said extension and adapted to be 85 seated on the said metallic collar.

In testimony whereof I have signed my name to this specification in the presence of two subscribing witnesses.

ARTHUR DOUGLAS NASH.
